BAR SUPPORT

Filed Feb. 7, 1930

UNITED STATES PATENT OFFICE

ROBERT R. ROBERTSON, OF CHICAGO HEIGHTS, ILLINOIS

BAR SUPPORT

Application filed February 7, 1930. Serial No. 426,456.

In concrete road construction work and reinforced concrete structures of different kinds, it has been the custom to embed a reinforcing mesh or screen together with transversely disposed dowel bars or rods in the concrete above the road sub-grade. The reinforcing mesh is usually constructed of rods or reinforcing members positioned at right angles with respect to one another and said 5 rods, where they cross, may be brazed or welded together or if preferred the reinforcing rods may cross one another or may be held in position by wedge members or the like.

To properly position a reinforcing mesh and dowel bars in position at different elevations above a road sub-grade, the present invention provides an improved support or bracket adapted to be conveniently positioned 20 to stand upon the road sub-grade to properly hold crossed reinforcing members wedged in seated engagement in recesses or brackets provided in the upper end of the support while the same bracket is adapted also to 25 afford a convenient support for a transversely positioned dowel bar.

It is an object of this invention to provide an improved light weight sheet metal bar support adapted to have crossed reinforcing 30 mesh rods supported on the upper end thereof and held in position by means of wedge keys while the intermediate portion of the bar support is constructed to afford a pocket support for a transversely disposed rod or 35 dowel bar which may be secured in place by bending over a lip forming a part of the support pocket for said dowel bar.

It is also an object of this invention to provide an improved bar support of unitary construction provided with recesses or pockets 40 for receiving crossed reinforcing members and dowel bars, said reinforcing members adapted to be locked in position by means of wedge keys or the like.

It is an object of this invention to provide 45 a metal reinforcement support adapted to be constructed of light weight sheet metal shaped to afford an angular apertured standard provided with integral supporting feet 50 at the lower end, while the upper end is pro-

vided with apertured lugs or fingers and with recesses for the reception of crossed reinforcing rods and wedge pins for locking said rods in position, said support furthermore having a dowel bar socket formed therein 55 and provided with a locking finger or extension which is adapted to be bent into a locking position over a dowel bar after the bar has been supported in place.

Other and further important objects of 60 this invention will be apparent from the disclosures in the specification and the accompanying drawing.

The invention (in a preferred form) is illustrated in the drawing and hereinafter 65 more fully described.

On the drawing:

Figure 1 is a fragmentary top plan view of a portion of a concrete road sub-grade having mounted thereon a plurality of spaced 70 improved bar supports embodying the principles of this invention and supporting crossed reinforcing bars or rods and dowel bars in position at different elevations above the sub-grade. 75

Figure 2 is a vertical sectional view taken on line II-II of Figure 1.

Figure 3 is a rear elevational view taken on line III-III of Figure 1 and illustrating an improved bar support embodying the 80 principles of this invention and showing the reinforcing rods and the dowel bar in supported position.

Figure 4 is a top plan view of the bar support illustrating the reinforcing rods and the 85 dowel bar in dotted line.

Figure 5 is a side elevation of the bar support with the reinforcing rods omitted and illustrating the dotted line locking position 90 of the dowel bar retaining finger.

Figure 6 is a front elevation of the bar support covering a modified arrangement at the upper end of the bar support for the reception of connected reinforcing rods or a rod mesh wherein the wedge members are 95 engaged only with the lowermost rods of the mesh to hold the same in seated position.

As shown on the drawing:

The reference numeral 1 indicates the sub-grade of a concrete road with the upper 100

strata or body of concrete which requires reinforcing being omitted. The road reinforcing mesh or screen for reinforcing the upper section of the concrete comprises a plurality of crossed bars or rods 2 and 3 and a plurality of dowel bars or rods 4 adapted to be positioned transversely of the road and adapted to be supported at an elevation below the elevation of the reinforcing bars or rods 2 and 3. The reinforcing rods 2 are positioned transversely of the road and are located beneath the reinforcing rods 3 which run longitudinally of the road and are free from attachment to the reinforcing rods 2.

15 The reinforcing rods 2 and 3 cross one another without being fastened together and are adapted to be supported by means of improved bar supports positioned at spaced intervals on the road sub-grade similar to the arrangement illustrated in Figure 1.

20 Each of the improved bar supports is of unitary construction and is adapted to be formed from a single strip of sheet metal.

The improved bar or rod support is adapted to be cut or stamped from a sheet of metal with the sections of the sheet metal which is to be bent into shape to form the bar support having a plurality of apertures or openings 5 and 6 provided therein to lighten the weight of the bar support. The section of sheet metal forming the blank from which the bar support is to be formed, also has cut or stamped from the middle sections thereof an inverted heart-shaped opening 7 which forms a finger or latch tongue 8. The lower end of the bar support blank is slotted or cut inwardly a short distance while the upper end of the blank is cut out to afford a pair of arms or lugs 9 having slots or apertures 10 therein. The two apertured arms 9 are separated by a notch 11 which provides an upper pocket or recess for receiving the upper reinforcing rods 3. Formed on each side of the upper portion of the blank is a rounded recess or pocket 12.

In a blank cut out or stamped from a sheet of material in the form hereinbefore described, the apertured or slotted blank is adapted to be folded into shape to provide the improved bar support. The blank is folded longitudinally along a central line to position the folds or flanges 13 at substantially right angles to each other after which the two sections at the lower end of the blank 55 are bent outwardly at right angles to the respective walls or flanges 13 to provide feet or stand plates 14. The heart-shaped aperture 7 provided in the blank affords an inclined pocket or seat for the reception of a dowel bar 4 and the finger or lug 8 formed by the heart-shaped opening 7 is adapted to be bent inwardly into the dotted line position illustrated in Figure 5 around the dowel bar 4 to hold the same locked in seated engagement with the bar support. When the blank

is folded as described, the two apertured lugs or arms 9 are positioned at substantially right angles with respect to one another and the two pockets or recesses 12 provided in the upper end of the walls 13 of the bar support afford seats for the lower reinforcing rods 2 as illustrated in Figure 3. The notches 12 are positioned lower than the notch 11 so that the crossed reinforcing rods 2 and 3 are adapted to be held locked in position in the upper end of the bar support by means of a wedge 15 which is projected through the slots or apertures 10 above the upper reinforcing rod or bar 3 to wedgingly hold the crossed rods or bars locked in place.

Figure 6 illustrates a modified form of rod and dowel bar support which is also of unitary construction formed from sheet metal and of substantially the same construction as the bar support illustrated in Figures 3 and 5 with the exception that the upper end of the bar support is provided with a deep central recess or pocket 16 and two side recesses or pockets 17 which are at a higher elevation than the intermediate pocket 16 to afford an arrangement whereby connected cross members forming a part of the rod reinforcing mesh are adapted to be seated in the upper end of the bar support with the lowermost rod or bar 18 seated in the intermediate recess or pocket 16 while the upper reinforcing bar or rod 19 is seated in the upper recesses or pockets 17 thereby affording an arrangement permitting the wedge member 15 to be inserted through the slots or apertures 10 in the arms or lugs 9 with the wedge member seated upon the lower rod or bar 18 to wedgingly hold the cross bars of the reinforcing mesh locked in a seated position since the cross bars are rigidly connected one to the other by means of a rivet or by brazing or welding the same together.

A plurality of the improved bar supports are adapted to be positioned at spaced intervals upon the road subgrade 1 as, for example, according to the arrangement illustrated in Figure 1, and the dowel bars 4 are adapted to be seated in the pockets 7 transversely of the road after which the fingers or retaining lugs 8 forming a part of the support are adapted to be bent over into the dotted line position illustrated in Figure 5 to hold the dowel bars locked in position.

After the dowel bars have been supported in position above the sub-grade, the transverse reinforcing rods or bars 2 are adapted to be seated in the pockets or notches 12 of transversely aligned bar supports, after which the longitudinally positioned reinforcing rods or bars 3 are adapted to be seated upon the transverse reinforcing rods 2 seated in the upper intermediate notches 11 of the bar supports. After the upper reinforcing rods or bars 2 and 3 are engaged in the series of bar supports positioned upon the road sub-

grade, the wedge members 15 are adapted to be engaged through the slots 10 of the bar support arms 9 with the wedges resting upon the upper reinforcing rods 3 as illustrated in Figure 3, thereby wedgingly holding or locking the crossed reinforcing bars or rods in proper position at a desired elevation above the road sub-grade.

After the reinforcing rods and the dowel bars have been supported in position upon the improved support as described, concrete is adapted to be poured over the sub-grade to embed the reinforcing rods and the dowel bars in addition to the supports to form the upper concrete section of the road. The concrete when poured is adapted to fill the openings and recesses provided in the bar supports and is also adapted to seat upon the feet or plates 14 to properly hold the bar supports in place on the sub-grade.

When a heavy wire reinforcing mesh or connected reinforcing rods are to be used similar to the arrangement illustrated in Figure 6, the dowel bars 4 are so supported in the pockets 7 of the supports after which the reinforcing mesh formed by the connected rods 18 and 19 is seated in the pockets or recesses 16 and 17. The wedge members 15 are next engaged through the slots of the arms 9 with the wedges seating wedgingly against the lower reinforcing rods or members 18 to hold the mesh locked in position seated upon the bar supports.

While the bar supports have been described as being arranged to afford seats or pockets for both reinforcing rods and dowel bars, it will of course be understood that the bar supports may be used for supporting the reinforcing rods only or, in certain cases, for supporting the dowel bars only.

The improved bar supports as described are constructed of light weight sheet metal bent into form to form rigid bar supporting constructions with which the wedge members are adapted to be associated for locking the reinforcing cross rods in position on the upper end of the bar support.

It will of course be understood that many changes may be made and numerous details of construction may be varied through a wide range without departing from the principles of this invention, and it is therefore not the purpose to limit the patent granted hereon otherwise than necessitated by the scope of the appended claims.

I claim as my invention:

1. A bar support comprising a pair of apertured walls integrally connected and positioned at an angle with respect to one another, feet integrally formed on the lower ends of said walls, said walls cut out to form a dowel bar pocket, a retaining finger formed by said dowel bar pocket adapted to be bent to hold a dowel bar locked in said pocket, a slot-

ted arm integrally formed on the upper end of each of said walls and separated by means of an intermediate pocket and having side recesses or pockets positioned to the outside thereof for the reception of crossed reinforcing rods adapted to be held locked in position by means of a wedge member engaged through the slotted arms. 70

2. A reinforcing mesh and dowel bar support comprising a sheet metal apertured body section bent to provide two walls positioned at an angle with respect to one another with said body sections having a dowel bar supporting pocket formed at the bend of the body portion, supporting feet integrally formed on the lower end of the body portion, and slotted arms integrally formed on the upper end of the body section and positioned at an angle with respect to one another, said body section having the upper end thereof 80 provided with a plurality of pockets positioned to the outside and between said arms for the reception of crossed reinforcing rods, and a wedge member removably engaged through the slotted arms for locking the reinforcing rods seated in position. 85

3. A bar support of the class described comprising an angle body section, feet integrally formed on the lower end thereof, and slotted arms integrally formed on the upper end of the body section and providing a plurality of notches on both sides of the arms for the reception of crossed reinforcing bars, and a wedge member adapted to be engaged through the slotted arms in engagement with one of said crossed reinforcing bars to hold the bars locked in position on the bar support. 95

4. A bar support of the class described comprising an apertured angle body section, feet integrally formed on the lower end thereof, said body section having a pocket formed therein in the line of bend of the body section to receive a dowel bar, a retaining finger integrally formed on the body section and adapted to be bent to engage the dowel bar to hold the same seated in position, slotted arms integrally formed on the upper end of the body section and affording a plurality of recesses at different elevations for the reception of crossed reinforcing members, and a wedge device removably engaged through the slotted arms for holding the reinforcing members wedgingly locked in position supported on the upper end of the bar support. 105 110 115 120

5. A bar support comprising an angled apertured body section having a dowel bar supporting pocket formed intermediate the ends thereof, a retaining finger integrally formed on the body section for holding the dowel bar locked in said pocket, said body section having the upper end thereof cut to provide a plurality of bar receiving pockets and a plurality of slotted arms, said pockets opening through the upper edge of the body 125 130

section and positioned to receive crossed reinforcing bars seated therein, and means engaging through said slotted arms for holding the crossed reinforcing bars locked seated in the upper end of the body section.

5 6. A bar support of the class described comprising an apertured angled body section, feet integrally formed on the lower end thereof, said body section having the upper end thereof cut to provide a plurality of bar supporting pockets and separated by a pair of apertured arms, said pockets arranged to receive crossed reinforcing bars seated therein, and a wedge member engaged through the apertured arms and contacting one of said

10 15 crossed reinforcing bars to hold the bars locked in seated position.

7. A bar support of the class described comprising an angled body section, feet integrally formed on the lower end thereof, 20 apertured arms integrally formed on the upper end of the body section, said body section having a rod receiving pocket provided there-in between said arm and a pair of rod receiving pockets formed therein to the outside of 25 said arms, said pockets arranged for the reception of crossed reinforcing members, and a wedge member adapted to be removably engaged through the apertured arms to hold the crossed reinforcing members seated in 30 locked position upon the upper end of the bar support.

8. A bar support comprising a sheet metal angled body section having a dowel bar receiving pocket formed therein intermediate 35 the ends thereof, a retaining member integrally formed on said body section adapted to be bent into locking engagement with the dowel bar after same is seated in said pocket, 40 feet formed on the lower end of said body section to support the bar support in position, said body section having a plurality of reinforcing bars supporting apertures provided therein, a pair of slotted arms integrally 45 formed on the upper end of said body section separating said bar supporting pockets, and a wedge member removably engaged in said slotted arms for wedgingly holding a pair of crossed reinforcing bars seated in said upper 50 pockets.

9. A bar support of the class described comprising a pair of integrally connected walls positioned at an angle with respect to one another and arms integrally formed on 55 the upper edges thereof and separated by a rod supporting pocket, said walls having the upper edges thereof cut out to provide rod supporting pockets for a rod positioned at right angles to the rod seated in the pocket 60 provided between said slotted arms.

In testimony whereof I have hereunto sub-scribed my name at Chicago, Cook County, Illinois.

ROBERT R. ROBERTSON.
